(57) **CLAIM**

The ornamental design for a receptacle, as shown and described.

DESCRIPTION

FIG. 1 is a front perspective view of a receptacle in a closed configuration showing the new design;

FIG. 2 is a bottom perspective view thereof;

FIG. 3 is a front view thereof;

FIG. 4 is a rear view thereof;

FIG. 5 is a right side view thereof, the left side view being a mirror image thereof;

FIG. 6 is a top view thereof; and

FIG. 7 is a bottom view thereof.

FIG. 8 is a front perspective view of the receptacle in an open configuration showing the new design;

FIG. 9 is a front view thereof;

FIG. 10 is a rear view thereof;

FIG. 11 is a right side view thereof, the left side view being a mirror image thereof;

FIG. 12 is a top view thereof; and,

FIG. 13 is a bottom view thereof.

The broken lines in the figures depict unclaimed features or portions of the receptacle and form no part of the claimed design. For clarity, vents on a lower front and rear portion of the receptacle as illustrated in FIGS. 2-5 and 9-11 are shown in broken lines and form no part of the claimed design.
